DENTAL HANDPIECE

Ralph Edward Grossman, 1270 E. 18th St.,
Brooklyn, N.Y. 11230

Filed Apr. 11, 1968, Ser. No. 11,409

Term of patent 14 years

Int. Cl. D24—03

U.S. Cl. D24—1

The broken lines are shown for illustrative purposes only.

I claim:

The ornamental design for a dental handpiece, as shown and described.
